U.S. Appl. No. 29/234,083, filed Jul. 13, 2005, Gaultier et al.

* cited by examiner

Primary Examiner—Carol Rademaker*(74) Attorney, Agent, or Firm*—Hiscock & Barclay, LLP(57) **CLAIM**

I claim the ornamental design for a flask, as shown and described.

DESCRIPTION

FIG. 1 is a top, front and right side perspective view of a flask, showing my new design;

FIG. 2 is a front elevational view thereof;

FIG. 3 is a top, rear and left side perspective view thereof, showing four small square magnets on the rear surface;

FIG. 4 is a rear elevational view thereof;

FIG. 5 is a right side elevational view thereof, the left side elevational view being a mirror image;

FIG. 6 is a top plan view thereof;

FIG. 7 is a top, rear perspective view thereof; and,

FIG. 8 is a bottom plan view thereof.
